UNITED STATES PATENT OFFICE.

HENRY G. PORTMANN, OF ST. LOUIS, MISSOURI, ASSIGNOR OF ONE-HALF
TO WILLIAM W. PORTMANN, OF SAME PLACE.

CENTER-BEARING SPRING FOR ROCKERS.

SPECIFICATION forming part of Letters Patent No. 390,898, dated October 9, 1888.

Application filed May 5, 1888. Serial No. 272,933. (No model.)

To all whom it may concern:

Be it known that I, HENRY G. PORTMANN, of the city of St. Louis, in the State of Missouri, have invented a certain new and useful Improvement in Reciprocating Center-Bearing Springs for Rockers, &c., of which the following is a full, clear, and exact description, reference being had to the accompanying drawings, forming part of this specification.

This invention relates to an improvement on my invention for combined child's carriage, cradle, and chair for which a patent was issued on January 31, 1888, No. 377,270; and it consists in a reciprocating rocker center-bearing spring with its hanger-links, that is especially adapted for attachment beneath the rockers of combined carriages, cradles, and rocking chairs such as are the subject-matter of my said patent, but may also be used as a subsidiary spring-balance attachment beneath all other elevated or raised rockers.

Figure I is a perspective view of one of the axles and rocker-springs of my combined carriage and cradle, as described and shown in the aforesaid patent, with the reciprocating rocker center-bearing spring attached beneath it. Fig. II is an enlarged detail, and shows the rocker, axle, and center-bearing spring with part broken away to fully show said spring and its means of attachment; and Fig. III is a vertical section taken on line III III, Fig. II, and shows the axle, the standard rising from said axle, the rocker within the slot in which said standard rises, the hanger-links, the upper screw-bolt that couples said links and rockers, the center-bearing spring, and its screw-bolted attachment to the hanger-links.

Referring to the drawings, in which similar figures of reference indicate like parts in all the views, 1 represents the axle.

2 is the rocker-section of the combination rocker-spring, which is secured to the spring-section 3, which it supports, by screw bolts or rivets 4, and together comprise the axle and rocker-spring of a combined child's carriage and cradle, as shown and described in my aforesaid patent.

5 is a vertical standard, that rises from the axle (with which it is integral) and passes through the slot 6 of the rocker.

7 represents the reciprocating rocker center-bearing spring, the loop 8 of which is pivotally secured between the two hanger-link plates 9 by the screw-bolt 10, which passes through the links at their lower ends and 55 through said loop, and, being secured by the screw-nut 11, the said bolt secures the lower end of the spring and the lower ends of the pendent links together. The spring curves around upward, and its upper flanged extremity, 12, is seated in the inverted socket 13 on the under side of the axle. The upper ends of the hanger-links are coupled together by the bolt 14, which also passes through the rocker-section and through the trapezoidal-shaped slot 15 in the standard 5, that rises from and is integral with the axle 1; and the screw-nut 16, which engages on said bolt, secures it in its seat, holds the pendent links that constitute hangers for the suspension of 70 the spring, and holds the rocker in rocking connection with the arched axle which it surmounts.

It will be seen that the hanger link plates keep the rockers definitely in line with the axles, or, in a rocking-chair, with the raised rocker tracks or platforms, and at the same time allows them free rocking movement along those lines, and the upper bolt, 14, that passes through the upper ends of the hangers, the 8c rockers, and the trapezoidal-shaped slots 15 in the standards 5, has given to it a free spring-actuated movement within said peculiar shaped slot that allows free exercise of the rockers along the lines of the axles, but will 85 not allow of any lateral adverse divergence from said lines.

The springs 7, which are hung directly beneath the middle of the axles and rockers, give to the latter, when set in motion, lively, easy 90 reciprocating movements both in rocking to and fro, and on arrival at each extremity of their movement insures their return to their center-bearings by the counteracting reciprocating movements of their center-bearing 95 springs, which are consequently balance-springs.

By the use of this reciprocating center-bearing spring and the hanger-links, by which it is suspended and by which it is held in line 100

with the axle or track (as the case may be) on which the rocker springs work, the difficulty is avoided that arises with rockers that work on raised or elevated tracks or platforms (as 5 the bearings become worn or strained) of divergence from the line of said tracks in their movements; also, there is in the center-bearing balance action of said subsidiary spring an easy, flexible, normal tendency exerted on 10 the spring-rockers to overcome the shock of the interchange of their reciprocating movement and smoothly glide from one into the other, the springs acting as balance springs to overcome the dead-centers in their movements. 15 I have shown and described my reciprocating center-bearing springs and hangers, especially in their adaptation as an attachment to my combined child's carriage, cradle, and rocking-chair; but I do not confine myself to 20 said application of the invention, for it is evident that it would be advantageously applicable to all forms of rockers, both spring and otherwise, of cradles, rocking-chairs, &c., in which the rockers are elevated or raised above 25 the floor, &c., where they are used. The said elevation of the rockers provides the needed opportunity for the attachment of my invention, (both the springs and the hangers that support them and guide them in line on their 30 tracks;) also, the smoothly - flexible spring movement that thus governs the rockers in all stages of their movements, especially in overcoming the dead-center in the reciprocating movement to and fro, peculiarly adapts it for 35 use on platform rocking-chairs for invalids and the aged and infirm, and also for my combined carriage and cradle or other elevated rocker-cradles when in use for weakly or invalid children. 40 When my reciprocating rocker center-bearing spring is used as an attachment to rocking-chairs or cradles other than a combined child's carriage and cradle, in which the flanged end of said reciprocating spring is seated in 45 the inverted socket 13 in the axle of said carriage, the said flanged end of the spring is secured in a similar inverted socket beneath the track-platform of said rocking-chair or cradle in substantially the same position in relation 50 thereto as it does in the other case to the axle.

I claim as my invention—

1. In cradles, rocking-chairs, children's carriages, &c., the combination of the combined rocker and spring, the track-bar on which said rocker works, the pendent links pivoted to the 55 rocker, so that they swing on line with said rocker, and the C-spring which is pivotally secured to and within said pendent links, substantially as and for the purpose set forth.

2. In cradles, rocking-chairs, children's carriages, &c., a reciprocating center-bearing C-spring beneath the rockers, and track-bar arranged as the rockers move to and fro to balance the movements as they alternate from one motion to the other, and the upper limb 65 of said spring, which exerts a fulcrumal reactionary pressure on the track-bar, substantially as and for the purpose set forth.

3. In cradles, rocking-chairs, children's carriages, &c., the combination of a reciprocating 70 center-bearing C-spring and the hanger-links by which it is suspended, the said hanger-links arranged by being pivoted to the rockers and hanging pendent past the axles to retain the rockers on line with their track, and the said 75 spring to balance the reciprocal movement of the rockers, and at the extremity of said movement to bring them back to their center-bearings, substantially as and for the purpose set forth.

4. In cradles, rocking-chairs, children's carriages, &c., the combination of the combined rocker and spring, the axle on which said rocker works, the slotted standard that rises from said axle and passes through said rocker, 85 the hanger-links, the bolt 14, that secures said hanger-links to the rocker and the rocker to the slotted standard of the axle, and the reciprocating center-bearing springs beneath the rockers, secured at one end to the foot of the 90 hangers and at the other end on an inverted socket beneath the axle or track-platform above, substantially as and for the purpose set forth.

HENRY G. PORTMANN.

In presence of—

BENJN. A. KNIGHT,
SAM'L KNIGHT.
